UNITED STATES PATENT OFFICE

JOHN H. FREEZE, OF CAPE GIRARDEAU, MISSOURI

BOAT

Application filed December 9, 1929. Serial No. 412,780.

This invention relates to a boat particularly of the somewhat houseboat type but yet may be used for carrying freight or any other desired purpose, and the prime object of the 5 invention resides in the provision of a boat of this nature which will draw but little water when in motion and capable of attaining a relatively high speed.

Another very important object of the 10 invention resides in the provision of a boat of this nature which will tend to rise in the water as it picks up speed.

A still further very important object of the 15 invention resides in the provision of a boat of this nature which is very simple in its construction, inexpensive to manufacture, strong and durable, economical, reliable, and efficient in operation and otherwise well adapted to the purpose for which it is designed.

20 With the above and other objects in view as will appear as the description proceeds, the invention resides in certain novel features of construction, in the combination and arrangement of parts as will be hereinafter 25 more fully described and claimed.

In the drawings:

Figure 1 is a side elevation of a boat embodying the features of my invention,

Figure 2 is a bottom plan view thereof,

30 Figure 3 is a rear elevation thereof,

Figure 4 is a fragmentary transverse vertical section taken substantially on the line 4—4 of Figure 2,

Figure 5 is a detail sectional view taken 35 substantially on the line 5—5 of Figure 2,

Figure 6 is a detail sectional view taken substantially on the line 6—6 of Figure 2, and

Figure 7 is a detail sectional view taken substantially on the line 7—7 of Figure 2.

40 Referring to the drawing in detail, it will be seen that the numeral 5 denotes a rectangular frame made strong and durable from which rises a suitable superstructure 6 designed in accordance with the taste of the 45 builder.

A plurality of transverse stationary axle shafts 7 are mounted on the under edges of the sides of the frame by means of suitable caps 8 or in any other desired manner. On 50 each shaft 7 there is rotatable a pair of spaced

drums 9 connected together by sleeves 10 rotatable on the central portions of the axle and journaled in the bearings of brackets 11 depending from the floor of the superstructure 6.

Each drum 9 is provided with a plurality of fins 12 extending radially from the periphery thereof, preferably two on each drum in diametrically opposed relationship. On each sleeve 10 there is a worm gear 14. A longitudinally extending shaft 15 is journaled in the front and rear ends of the frame and has a plurality of worms 16 thereon meshing with the worm gear 14.

Suitable gearing 17 operatively connects 65 this shaft 15 with a prime mover inside the superstructure 6. Propellers 18 are mounted on the rear end shafts 19 journaled through the rear end of the frame and chain and sprocket mechanisms 20 operatively connect 70 the shafts 19 with the shaft 15.

When the shaft 15 is placed in operation all 75 the drums rotate at the same time and at the same speed and this, of course, moves the boat in the direction desired depending, of course, on the direction of rotation of the drums and rotation of these drums not only have a tendency to move the boat but also to raise the boat out of the water so as to eliminate friction to a considerable extent.

In actual use the water line would be about 80 where the dotted line is shown in Figure 3 noted by numeral 23 and when the boat is in motion it will rise so that the frame 5 is practically out of the water. The propellers 85 18 assist in the forward movement of the boat and tend particularly to offset suction at the rear thereof.

It is thought that the construction, utility and advantages of this invention will now 90 be quite apparent to those skilled in this art without a more detailed description thereof.

The present embodiment of the invention has been disclosed in considerable detail merely for the purposes of exemplification since in 95 actual practice it attains the features of advantage enumerated as desirable in the statement of the invention and the above description.

It will be apparent that changes in the de- 100

tails of construction, and in the combination and arrangement of parts may be resorted to without departing from the spirit or scope of the invention as hereinafter claimed or sacrificing any of its advantages.

5 Having thus described my invention, what I claim as new is:

1. In a boat of the class described, a frame, a plurality of transverse shafts in the frame, a pair of drums on each shaft, sleeves journaled on the shafts and connecting the drums, worm gears on the sleeves, a longitudinal shaft, worm portions on the longitudinal shaft connecting with the worm gears, and means for rotating the longitudinal shaft.
- 10 2. In a boat of the class described, a frame, a plurality of transverse shafts in the frame, a pair of drums on each shaft, sleeves journaled on the shafts and connecting the drums, worm gears on the sleeves, a longitudinal shaft, worm portions on the longitudinal shaft meshing with the worm gears, a pair of propeller shafts rotatably supported in one end of the frame, one to each side of said longitudinal shaft, chain and sprocket mechanisms operatively connecting said longitudinal shaft with said propeller shafts, and means for rotating said longitudinal shaft.
- 15 3. A boat, having in combination, a plurality of pairs of propeller drums, a supporting shaft for the drums of each pair of drums, said shaft being arranged in longitudinal spaced relation, an actuating shaft for the first mentioned shaft and having its axes at right angles to the axes of the first mentioned shafts, means rotatable on said first mentioned shaft, and operatively connecting the drums of the respective pairs of drums, said means also including means operatively connected with the last referred to shaft, a pair of screw propellers, supporting shafts therefor, mechanism common to said propeller shafts and said last mentioned shafts for simultaneously actuating said drums and said propellers, and fins radiating from said drums.

In testimony whereof I affix my signature.
JOHN H. FREEZE.
